DESIGN FOR A CHRISTMAS WREATH AND THE LIKE

Charles S. Price, Hollis, N. Y.

Application January 30, 1942, Serial No. 105,525

Term of patent 14 years

To all whom it may concern:

Be it known that I, Charles S. Price, a citizen of the United States, residing at Hollis, in the county of Queens, Long Island, and State of New York, have invented a new, original, and ornamental Design for a Christmas Wreath and the like, of which the following is a specification, reference being had to the accompanying drawing, forming part thereof.

Figure 1 is a face view of a Christmas wreath, showing my new design.

Figure 2 is a face view of one of the elements of the wreath enlarged as compared with Figure 1.

Fig. 3 is an enlarged fragmentary face view of the "Merry Christmas" portion of the design.

Figure 4 is a sectional view on the line IV—IV of Figure 2, in the direction of the arrows.

The drawing is lined to indicate color contrasts as shown.

It will be understood that the dotted line portions illustrated in the drawing will, in the actual design, be filled in the same as those shown in full lines, so that the surface ornamentation is complete over the entire face of the article, which comprises four ornaments as in Figure 2 with their ends joined and the assembly overlapped by the "Merry Christmas" design, with surface ornamentation also completed, as indicated in Figure 3.

I claim:

The ornamental design for a Christmas wreath and the like, substantially as shown and described.

CHARLES S. PRICE.
